UNITED STATES PATENT OFFICE.

COLEMAN C. LYDON, OF MINNEAPOLIS, MINNESOTA.

TABLE-PAD.

1,143,342.

Specification of Letters Patent. Patented June 22, 1915.

Application filed September 13, 1913. Serial No. 789,677.

To all whom it may concern:

Be it known that I, COLEMAN C. LYDON, a citizen of the United States, residing at Minneapolis, in the county of Hennepin and State of Minnesota, have invented certain new and useful Improvements in Table-Pads; and I do hereby declare the following to be a full, clear, and exact description of the invention, such as will enable others skilled in the art to which it appertains to make and use the same.

My invention relates to so-called table pads or table top protectors, and has for its object to improve the same in the several particulars hereinafter noted.

Particularly, the invention is directed to the provision of an extremely simple and highly efficient means for anchoring the pad to the top of an extension table.

20 In the accompanying drawings which illustrate the invention, like characters indicate like parts throughout the several views.

Referring to the drawings Figure 1 is a perspective view showing an extension table 25 of the solid pedestal type; Fig. 2 is a plan view of one of the main sections of the pad; Fig. 3 is an edge elevation of the parts shown in Fig. 2; Fig. 4 is an enlarged vertical section taken on the line $x^4 x^4$ on Fig. 30 2, some parts being broken away; and Fig. 5 is a vertical section taken through the pad and table top approximately on the line $x^5 x^5$ on Fig. 1.

Of the parts of the table, the numeral 1 35 indicates the pedestal, the numeral 2 the slidable separable table top sections, and the numeral 3 an extension board.

The table top protector, as shown, is designed to fit a round table top but may, of course, take other forms. It is, therefore, made up of two semi-circular main pad sections 4, and also, preferably, of one or more extension pad sections 5. The main sections 4 fit the main table top sections 2, and the extension pad 5 fits the extension board 3. In this preferred construction, each of the pad sections 4—5, is made up of upper and lower parts 4^a and 4^b. The said upper part 4^a may be a single ply of heavy paper, felt, or other suitable material, while the said lower part 4^b is preferably made up of two plies of the same material. The upper part 4^a is preferably covered with oil cloth or other liquid-proof material 4^c, which, at its edge, is turned under the said top part 4^a. The lower part 4^b is preferably pro-

vided with a bottom covering of flannel or other cloth 4^d, the edge of which is brought up and turned over the top of the said part 4^b. The two parts 4^a and 4^b are then placed together with the inturned edges of the coverings 4^c and 4^d pressed together, leaving a strong and nicely finished edge around the pad. The oil cloth or water proof covering 4^c, of one of the main pad sections 4, and also of the extension pad 5, is preferably extended to form a flexible joint flap 4^e, which is in the form of a loop, being formed by having its extreme edge folded backward and secured to the upper felt plies 4^a. This gives a strong and durable joint flap which will not fray out.

The anchoring devices are in the form of flexible straps constructed of canvas or other suitable material, the said straps being 75 preferably doubled to form loops 6, the ends of which are extended between the upper and lower plies 4^a and 4^b of the several sections of the pad. The upper and lower plies of the pad sections may be secured together, 80 as above stated, by the use of cement, or by being stitched, and in either instance, the ends of the anchoring loops 6 will be firmly secured to the respective pad sections. The anchoring loops 6 which are on the adjacent 85 edges of different pad sections and which drop between the same joint between sections of the table top, are offset so that they do not come into engagement with each other and so that when pinched between the 90 sections of the table top, they will not separate the said table top sections to any considerable extent. They will, however, when thus clamped, securely anchor the pad sections to the table top and properly position 95 the same thereon.

By pulling on the lower ends of the anchoring loops just before or while clamping the table top sections against the same, close and accurate positioning of the pad sections and the table top sections is insured. Being flexible and pliable, the said anchoring straps will not mar the table top and are adapted to be compressed, so that they will 100 separate the table top sections only very 105 slightly. When pinched in the joints between the table top sections, the said anchoring straps will be very firmly held. When the pad is removed from the table it does not afford obstructions or projections interfering with close packing of the pads. To 110 facilitate packing or storage of the pad sec-

tions when removed from the table top, the several sections are preferably formed with hinge folding joints 7.

What I claim is:

- 5 1. A table top protector made up of rigid sections, having at their abutting edges depending flexible straps permanently attached thereto and adapted to be pinched between the sections of a table top, said straps extending below the table top and affording hand pieces by which the sections of the table top protector may be pulled into place before the straps are pinched by the closing of the table top sections.
- 10 2. A table top protector made up of rigid sections, each section being made up of upper and lower plies and coverings therefor, said sections having at their abutting edges

depending flexible anchoring straps, the upper ends of which are interposed between 20 the upper and lower plies of said sections permanently secured thereto and adapted to be pinched between the sections of a table top, said straps extending below the table top and affording hand pieces by which the 25 sections of the table top protector may be pulled into place before the straps are pinched by the closing of the table top sections.

In testimony whereof I affix my signature 30 in presence of two witnesses.

COLEMAN C. LYDON.
